BUILDING SET

James M. Leake, Toledo, Ohio

Application September 20, 1932, Serial No. 634,024

8 Claims. (Cl. 46—37)

This invention relates to a building set designed primarily for the entertainment and instruction of children, although it embodies some novel features which may be used in standard building construction.

One object of the invention is to provide a building set having pieces adapted to be associated in such a manner that various attachments may be secured thereto to produce buildings of various styles.

The novel features embodied in the invention include a sloping roof hinged at the top and having the side of the building hinged thereto and depending beneath the eaves, a Dutch colonial roof attachment, a novel door and window frame construction, a novel hinge construction in connection with the door and window frames, a one-piece porch, and various interchangeable features as hereinafter described.

The invention, in its preferred form, will be more specifically explained in connection with the accompanying drawings in which:

Fig. 1 is an isometric view of one of the buildings embodying the invention, a part of the roof and front side of the building being shown in raised position;

Fig. 2 is a detail view of a part of one of the partitions;

Fig. 3 is a detail view of a part of one of the floors;

Fig. 4 is a detail view of the porch or entry;

Fig. 5 is a detail view of the front step;

Fig. 6 is a detail view of one of the chimneys;

Fig. 7 is an isometric view of a bungalow which may be constructed according to the invention;

Fig. 8 is a detail view of one of the windows;

Fig. 9 is a detail view of the outside window frame;

Fig. 10 is an enlarged sectional view taken on the line 10—10 of Fig. 8;

Fig. 11 is a detail view of one of the interior attachments;

Fig. 12 is a detail view of one of the attachments which may be used interchangeably with that shown in Fig. 11;

Fig. 13 is a detail view of a window equipped with an awning in place of the shutters;

Fig. 14 is a side elevation of the construction shown in Fig. 13;

Fig. 15 is an isometric view of a garage which may be constructed according to the invention.

All of the various pieces of the set are adapted to be made from sheet metal. The set includes corner posts 1 and girders 2, made in the form of angle bars. These pieces, as well as other

pieces of the set, may be secured in assembled relation by screw bolts 3 or other suitable fastening elements. Partitions, stairways and other interior attachments may be provided and provision may be made for securing them in position according to the plan of the building to be erected. Fig. 1 represents a two-story house having a center hall plan, as indicated by the partitions 4.

Instead of providing all of the girders as separate angle bars, the floors 5 may be provided with integral flanges 6, as illustrated in Fig. 3, thereby reducing the number of separate pieces in the set. Some or all of the partitions 4 may be provided with similar flanges 6 for the same purpose. Strips 7 are adapted to be secured to the lower ends of the corner posts 10 and are formed and painted to represent a brick foundation.

The ends 8 of the building are adapted to be secured directly to the corner posts 1, while the front and rear sides 9 are secured to corner strips 10, which are hinged at 11 to the lower ends of the gable roof strips 12. The roof pieces 13 are secured to the upper faces of the strips 12, and the latter are provided at their upper ends with ears 14 to form hinges, so that the front or rear side of the building, together with the adjacent side of the roof may be raised as shown in the upper part of Fig. 1 to provide free access to the interior of the building for the purpose of arranging the fixtures or furniture therein.

It is preferred to provide a chimney 15 at each end of the building, and the same screw bolts which secure the chimney to the end of the building may also be used to secure the latter to the floor flanges or girders. The upper ends of the chimneys 15 are also useful in providing supports for the hinges 14. The front entrance or porch 16 may be formed from one piece of sheet metal and provided with a roof 17 and front step 18. The porch is secured by the same screw bolts which secure the front door frame to the front side 9.

Each door and window frame 18, as illustrated in Figs. 8, 9 and 10, consists of inside and outside rectangular strips which are secured by screw bolts passing through the siding. The outside strip is provided with struck out lips 20 and the inside strip is provided with struck out lips 21, which are inserted through the holes left by the lips 20 so that each pair of lips 20 and 21 meet to form a hinge eye 22 for supporting a shutter or door 23. In assembling a window

100

105

110

frame, therefore, the shutter is first mounted on the lips 20 and then the lips 21 are inserted to complete the hinge.

Each corner board 10 on the front and rear 5 sides of the building is slightly bent at its lower end to form a spring clip 24 which engages a knob on the corner of the building to retain the side in closed position.

The members 8 and 9 constitute the ends and 10 sides of a plain two-story house with a gable roof 13. This may be easily converted into a Dutch colonial style by the addition of a roof strip 25 which is provided with end strips 26 adapted to be secured to the roof strips 12, as 15 shown in Fig. 1.

The interior of the building may be provided with a great variety of differently arranged partitions, and the corners may be provided with various interchangeable attachments, as for example, a wash basin 27, a fireplace 28, and the 20 like.

The windows may be provided with awnings 29 instead of the shutters 23. Each awning may be conveniently provided with pins 30 adapted to be 25 inserted in the hinge eyes 22, as illustrated in Figs. 13 and 14.

The bungalow illustrated in Fig. 7 is constructed in the same manner as the house illustrated in Fig. 1 and largely from the same pieces. The 30 chimney 15^a, however, is shorter than the chimney 15, and the ends 8^a and sides 9^a are correspondingly of less height than the corresponding parts in the two-story building.

The garage illustrated in Fig. 15 is constructed 35 in the same manner as the other buildings except that the chimney is omitted, and the front side 9^b is provided with garage door frames 19^b instead of frames 19.

While I have shown and described the more important 40 features of the invention, it will be understood that these may be variously modified and numerous other attachments and accessories, interchangeable or otherwise, may be provided without departing from the scope of the invention 45 as claimed.

What I claim is:—

1. A building set comprising a piece constituting 45 a side of the building and having an opening therein, a frame for said opening including inside and outside pieces with lips struck out therefrom and cooperating to form a hinge eye when the inside and outside frame pieces are assembled.

2. A building set comprising a piece constituting 50 a side of the building and having an opening therein, a frame for said opening including inside and outside pieces with lips struck out therefrom, the lip on one frame piece, when the pieces are assembled, extending through the hole left by

the lip on the other piece and meeting said last mentioned lip to form a hinge eye.

3. A building set comprising a piece constituting 80 a side of the building and having an opening therein, a frame for said opening including inside and outside pieces with lips struck out therefrom and cooperating to form eyes when the outside and inside frame pieces are assembled, and an awning having pins secured thereto and insertable in said eyes to support the awning.

4. A building set comprising a piece constituting 85 a side of the building and having an opening therein, a frame for said opening including inside and outside pieces with lips struck out therefrom, the lips on one frame piece, when the pieces are assembled, extending through the respective holes left by the lips on the other piece and meeting the same to form eyes, and an awning having pins secured thereto and insertable in the respective eyes to support the awning.

5. In a building set, the combination of two members each having an opening therein, means 90 for securing said members with said openings in registry, means integral with the respective members and cooperating to form a hinge eye when said members are so secured, and a member co-operating with said eye to constitute a closure for said openings.

6. A building set comprising pieces for forming 95 the framework, sides, ends and gable roof of a two-story building, means for connecting said pieces to form a building of conventional type, and an attachment comprising a one-piece roof member attachable to said gable roof to convert the building into one conforming to Dutch colonial 110 style.

7. A building set comprising pieces constituting 115 the sides and ends of a two-story building and a gable roof therefor with overhanging ends, means for detachably connecting said pieces to 120 form said building, and an attachment comprising a single unit in the form of a roof strip adapted to extend from end to end of the building beneath the upper windows of one side, with legs extending from the ends of the strip to intermediate points of said overhanging ends of the gable roof and detachably secured thereto to simulate the Dutch colonial style.

8. A building set comprising pieces for forming 125 the framework, sides and ends of a building, means for securing said pieces rigidly in assembled relation, two chimneys adapted to be attached to opposite ends of the building, hinge pins secured to the inner opposed faces of the respective chimneys at the ridge pole of the building, and a 130 gable roof comprising two opposite slopes with upwardly projecting ears pivotally mounted on said pins.

JAMES M. LEAKE.
